ROLLBACK TOY

Earl R. Biggs, Portland, Oreg.

Application October 31, 1947, Serial No. 142,251

Term of patent 14 years

(Cl. D34—15)

To all whom it may concern:

Be it known that I, Earl R. Biggs, a citizen of the United States, residing at Portland, county of Multnomah, and State of Oregon, have invented a new, original, and ornamental Design for Rollback Toy, of which the following is a specification, reference being had to the accompanying drawing, forming part thereof.

In the drawings Fig. 1 is a side elevational view of the rollback toy, showing my new design; Fig. 2 is an end view of the toy in the position shown in Fig. 1; Fig. 3 is a view similar to Fig. 1 showing the toy rolled to a position at 90° to the position of Fig. 1; Fig. 4 is an end view of Fig. 3; Fig. 5 is a view of the toy rolled to a position at 180° to the position of Fig. 1; and Fig. 6 is an end view of Fig. 5.

The dominant features of my new design are shown in solid lines in the drawing.

I claim:

The ornamental design for a rollback toy, substantially as shown and described.

EARL R. BIGGS.
